UNITED STATES PATENT OFFICE.

PETER FLANSBURG, OF MANISTEE, MICHIGAN.

SHIPPING-CRATE.

1,256,458.

Specification of Letters Patent. Patented Feb. 12, 1918.

Application filed September 15, 1916. Serial No. 120,815.

To all whom it may concern:

Be it known that I, PETER FLANSBURG, a citizen of the United States, residing at Manistee, in the county of Manistee and State of Michigan, have invented certain useful Improvements in Shipping-Crates, of which the following is a specification, reference being had therein to the accompanying drawing.

10 This invention relates to improvements in shipping crates, one object of the invention being the provision of a crate consisting of an outer and inner crate, the outer crate of which carries resilient supporting members 15 for the inner crate, so that perishable goods may be supported without being damaged in transit, while a novel form of lid supporting and locking means for the outer crate is provided. Another object of the invention 20 is the provision of a shipping crate of this character wherein the inner crate is constructed and supported in a manner to assure thorough ventilation so that the contents of the carrier for the goods will be 25 rendered cool and dry thereby preventing molding and rotting of such goods within the carrier.

A further object of this invention is the provision of a shipping crate which is 30 simple, durable and inexpensive in construction, and thoroughly efficient and practical in use.

In the accompanying drawings:

Figure 1 is a longitudinal sectional view 35 and

Fig. 2 is a cross sectional view thereof.

Referring to the drawings, the numeral 5 designates the outer casing of the present 40 crate which is of open structure and is provided with the four corner posts 6 and with the bottom slats 7.

Attached to the bottom slats upon the interior of the casing by means of staples or other fastening devices 8 are the terminals 45 9 of the resilient supporting member 10, there being two of these members and each being made from a single strand of wire.

The inner crate or goods carrying member is adapted to rest upon these springs or 50 resilient supports which tend to hold the same upwardly and in close contact with the

underside of the removable top or cover 11 of the present shipping crate. The resilient supporting members 10 each is formed with a shoulder on each side which serves to hold 55 the inner crate in place as will be apparent.

In order that the cover may be properly supported and be readily released or secured in place, without the use of nails or screws, there is attached to each one of the posts 60 the staples 12 which receive the respective hooked terminals 13 of the two U-shaped bails 14 and 15.

The bail 14 is adapted to surround one end of the top or cover and be hingedly connected thereto by means of the staples 16, while the bail 15 is adapted, when the cover is in sealing position, to fit upon the opposite end of the cover, and thus resiliently hold the cover closed and the inner crate 70 cushioned upon its spring support.

Mounted in one end of the outer crate is the hook shank 17 having the eye which is loosely or pivotally connected upon supporting terminal 18 the hook shank 17 is provided with the eye 19 which is adapted to coöperate with the staple 20 carried by the cover to receive a padlock, so that the cover may be securely held in position during 80 shipment.

From the foregoing description, it is evident that with a crate equipped with the present attachments, the cover may be readily released and secured without the employment of nails or other fastening devices. At the corners of the crates are reinforcing plates or straps 21, it being understood of course that the body of the outer crate can be changed or altered in the construction thereof as the occasion may require 90 and as comes properly within the scope of the claim hereunto appended without departing from the spirit of the invention or sacrificing any of its advantages.

The resilient supports for the inner crate, 95 as well as the inner crate, may be dispensed with, as the outer casing may be used as a shipping crate alone.

What I claim as new is:

In a device of the character described in 100 combination an outer and an inner crate, a pair of similarly shaped fastening devices

each being formed from a single length of resilient wire bent into a substantial U-shape and having right angular terminals secured directly upon the bottom of the outer crate, and having upwardly inclining side portions bent back downwardly and terminating in a U-shaped substantially

horizontally and transversely disposed resilient supporting member upon which the inner crate is mounted in spaced relation 10 from the bottom of the outer crate.

In testimony whereof I affix my signature.

PETER FLANSBURG.
